JOURNAL BOX AND FRAME CONNECTION

Richard J. Brittain, Jr., Bloomfield, N. J., assignor to General Motors Corporation, Detroit, Mich., a corporation of Delaware

Application February 20, 1931. Serial No. 517,153

12 Claims. (Cl. 105—223)

This invention relates to journal box and frame connections and comprises all the features of novelty herein disclosed. An object of the invention is to provide an improved seat plate construction for rockably mounting a load carrying member with respect to a journal box. Another object is to provide a seat plate construction which provides for close approach of the load carrying member to the box, thus diminishing over-all height. To these ends and also to improve generally upon devices of this character, the invention consists in the various matters hereinafter described and claimed.

In its broader aspects, the invention is not necessarily limited to the specific construction selected for illustrative purposes in the accompanying drawing in which

Fig. 1 is one-half end view and one-half cross section of a portion of an axle box and its associated members.

Fig. 2 is a side view.

Fig. 3 is a vertical, longitudinal section.

Fig. 4 is a plan view of one half of the box and associated parts.

Fig. 5 is an isometric view of one of the lower seat plates.

The numeral 10 indicates a shaft or axle carrying a raceway sleeve 12 for a roller bearing 14 having cage rings 16. The rollers run in an outer sleeve or raceway 18 carried in a housing or axle box 20 and the cage rings are guided by bronze rings 22 riveted to flanges on the box. The box is preferably divided into two sections which meet at axle level, as indicated at 23, the upper section having depending portions 24 embracing a lower section 26, the two sections being clamped together by bolts 28. At each side, the box carries spaced pedestal flanges 30 which are covered by wear plates 32, the latter projecting from a flat body plate 34 covering the side of the box and having a bent end 36 welded to the top of the box. One end of the box also carries arcuate liner plates 38, preferably of bronze, to take the wear of the adjacent wheel hub.

The foregoing is not per se a part of my invention which resides chiefly in the construction by which load carrying members are supported on the box. At the top of the box and at each side of the center is a rectangular cavity 40 receiving and confining, from any material shifting, a lower seat plate comprising a base 42 and an upwardly projecting end lug 44. The base has its upper surface 46 convex or crowned longitudinally of the axle and the box on a curve of large radius. There is a small clearance at

48 between the top of the box and an equalizer or upper seat plate 50. Plate 50 has a comparatively thin section along its longitudinal middle portion and the lower surface of this is rounded longitudinally of the axle and the box as indicated in Fig. 3 to insure a clearance during rocking. The plate also has its opposite side portions thickened and the lower surfaces 52 thereof are convex or crowned longitudinally of the axle, each surface 52 being rockable on one of the above mentioned surfaces 46 of the lower seat plate. The upper seat plate has the middle of its opposite sides cut out to leave cavities at 54, each cavity receiving one of the lugs 44. The lugs and cavities have a little clearance and their adjacent side surfaces are curved on substantially the same radius so that the upper seat plate and the two lower seat plates can have a rocking motion with respect to one another without allowing the upper seat plate to shift bodily or become displaced from the box.

The seat plate 50 has transverse reinforcing ribs or webs 56 running crosswise of the box while extensions of the plate have parallel ribs 60 making channels 62 for load carrying members such as equalizer bars 64. The bottom of each channel is slightly crowned transversely of the seat plate and box so that the equalizer bars can rock a little and adjust themselves to the upper seat plate. The provision of the two lower seat plates at opposite sides of the axle reduces the overall height because the equalizer bars can be brought close to the box with only the thickness of the upper seat plate and the little clearance at 48 intervening. The load is not only low with respect to the box but is better distributed on the bearing rollers, the tendency being to decrease the load on that roller which is directly over the axle, this being the one which usually is subjected to the greatest stress.

I claim:

1. In a device of the character described, a journal box, a frame bar extending transversely over the top of the box and in close proximity thereto, a seat plate having a thin middle section supporting said frame bar and clearing the top of the box, and said plate having thickened side portions at opposite sides of the longitudinal center of the box and crowned longitudinally thereof; substantially as described.

2. In a device of the character described, a journal box, a frame bar extending transversely over the top of the box and in close proximity thereto, a seat plate having a thin middle section

supporting said frame bar and clearing the top of the box, said seat plate having its opposite sides crowned longitudinally of the box and provided with cavities, and holding means extending upwardly from the box into said cavities; substantially as described.

3. In a device of the character described, a journal box, a frame bar extending transversely over the top of the box and in close proximity thereto, a seat plate having a thin middle section supporting said frame bar and clearing the top of the box, lower seat plates mounted on the top of the box at opposite sides of the longitudinal center, the lower seat plates and the opposite sides of said first seat plate having engaging surfaces relatively crowned longitudinally of the box; substantially as described.

4. In a device of the character described, a journal box, a frame bar extending transversely over the top of the box and in close proximity thereto, a seat plate having a thin middle section supporting said frame bar and clearing the top of the box, lower seat plates mounted on the top of the box at opposite sides of the longitudinal center, the lower seat plates and the opposite sides of said first seat plate having engaging surfaces relatively crowned longitudinally of the box, and the lower seat plates and the first seat plate having inter-engaging holding lugs and cavities; substantially as described.

5. In a device of the character described, a journal box, a frame bar extending transversely over the top of the box and in close proximity thereto, a seat plate having a thin middle section supporting said frame bar and clearing the top of the box, the box having cavities at opposite sides of the longitudinal center, lower seat plates in said cavities and confined from bodily shifting by the side walls of the cavities, and the opposite sides of the first seat plate having rocking engagement with said lower seat plates; substantially as described.

6. In a device of the character described, a journal box, a frame bar extending transversely over the top of the box and in close proximity thereto, a seat plate having a thin middle section supporting said frame bar and clearing the top of the box, the box having cavities at opposite sides of the longitudinal center, lower seat plates in said cavities and confined from lateral and longitudinal shifting by the side walls of the cavities, the opposite sides of the first seat plate having rocking engagement with said lower seat plates, and said lower seat plates having upwardly extending holding lugs entering cavities at opposite sides of the first seat plate and embracing portions of the first seat plate to prevent its shifting crosswise of the box; substantially as described.

66 7. In a device of the character described, a

journal box, a pair of equalizer bars extending transversely over the top of the box and in close proximity thereto, a seat plate having its upper surface provided with spaced-apart seats for said equalizer bars, the central portion of said plate clearing the top of the box and having its lower surface rounded longitudinally to provide clearance for rocking, and the opposite sides of the seat plate having a rockable mounting at opposite sides of the longitudinal center of the box; substantially as described.

80 8. In a device of the character described, a journal box, lower seat plates carried by the top of the box at opposite sides of the longitudinal center, means for holding the plates from shifting bodily in any direction with respect to the box, an upper seat plate clearing the top of the box and having its opposite sides rockably engaging the lower seat plates, and a load carrying member engaging the upper seat plate over the longitudinal center of the box; substantially as described.

85 9. In a device of the character described, a journal box, an axle journaled in the box, a seat plate substantially co-extensive with the top of the box and having a small clearance therewith above the axle, the seat plate having its opposite sides crowned and rockably supported at opposite sides of the longitudinal center of the box, and a load carrying member engaging the upper surface of the seat plate over the axle; substantially as described.

90 10. In a device of the character described, a seat plate having upwardly projecting transverse ribs forming a grooved seat, the plate having a thin section at its longitudinal middle portion with thicker portions at opposite sides, and the thickened side portions having their lower surfaces crowned longitudinally; substantially as described.

95 11. In a device of the character described, a seat plate having upwardly projecting transverse ribs forming a grooved seat, the plate having a thin section along its longitudinal middle portion, the lower surface of said middle portion being rounded longitudinally, the plate having thickened portions at opposite sides, and said thickened portions having their lower surfaces provided with rocker surfaces; substantially as described.

100 12. In a device of the character described, a seat plate having a transverse groove on its upper surface, the bottom of the groove being crowned, the plate having a thin section at its longitudinal middle portion with thicker portions at opposite sides, and the side portions having their lower surfaces crowned longitudinally; substantially as described.
